(57) **CLAIM**

I claim the ornamental design for a wheelchair motorbike, substantially as shown and described, and

DESCRIPTION

FIG. 1 is a top front left perspective view of the wheelchair motorbike of the claimed invention with ramp in up position; FIG. 2 is a top rear right perspective view of the wheelchair motorbike;

FIG. 3 is a bottom front right perspective view of the wheelchair motorbike;

FIG. 4 is a right elevational view of the wheelchair motorbike with ramp in up position;

FIG. 5 is a left elevational view of the wheelchair motorbike.

FIG. 6 is a front view of the wheelchair motorbike of the claimed invention with ramp in up position;

FIG. 7 is a back view of the wheelchair motorbike with ramp in up position;

FIG. 8 is a top plan view of the wheelchair motorbike with ramp in up position;

FIG. 9 is a bottom view of the wheelchair motorbike with ramp in up position;

FIG. 10 is a top front left perspective view of the wheelchair motorbike of the claimed invention with ramp deployed;

FIG. 11 is a top rear right perspective view of the wheelchair motorbike with ramp deployed; and,

FIG. 12 is a top plan view of the wheelchair motorbike with ramp deployed.
